(57) **CLAIM**

The ornamental design for a decorative rim for a container, as shown and described.

DESCRIPTION

FIG. 1 is a top, right side and front perspective view of a decorative rim for a container showing the new design;

FIG. 2 is a front elevation view; the rear elevation view being identical thereto;

FIG. 3 is a right side view; the left side view being identical thereto;

FIG. 4 is a top plan view thereof; and,

FIG. 5 is a bottom plan view thereof.

The broken lines of a container shown in FIGS. 1-5 are for illustrative purposes only and form no part of the claimed design.
